US0D1106951S

(12) **United States Design Patent** (10) **Patent No.:** **US D1,106,951 S**
(45) **Date of Patent:** **** Dec. 23, 2025**

(54) **3-IN-1 WIRELESS CHARGER**

(71) Applicant: **Qinghai Lin**, Maoming (CN)

(72) Inventors: **Chang Dong**, Shenzhen (CN); **Qinghai Lin**, Shenzhen (CN)

(73) Assignee: **Qinghai Lin**, Maoming (CN)

(**) Term: **15 Years**

(21) Appl. No.: **29/930,323**

(22) Filed: **Feb. 29, 2024**

(51) **LOC (15) Cl.** **13-02**

(57) **CLAIM**

The ornamental design for a 3-in-1 wireless charger, as shown and described.

DESCRIPTION

FIG. 1 is a front, right, top perspective view of a 3-in-1 wireless charger, showing my new design;

FIG. 2 is a rear, left, bottom perspective view thereof;

FIG. 3 is a rear, right, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a front, right, top perspective view thereof, shown in a folded configuration.

The dashed broken lines in the figures illustrate portions of the 3-in-1 wireless charger that form no part of the claimed design.

1 Claim, 10 Drawing Sheets
